[57] CLAIM

The ornamental design for a hook for bungee cord, as shown and described.

DESCRIPTION

FIG. 1 is a perspective view of a hook for bungee cord showing my new design in a closed position with the broken line showing of a partial bungee cord being for illustrative purposes only and forming no part of the claimed design; FIG. 2 is a first side elevational view thereof, the other side elevational view being identical thereto; FIG. 3 is a first end elevational view thereof; FIG. 4 is a second end elevational view thereof; FIG. 5 is a top plan view thereof; FIG. 6 is a bottom plan view thereof; and, FIG. 7 is an enlarged perspective view of the design shown in FIG. 1 in an opened position.
